CLAIM

The ornamental design for a toilet brush, as shown and described.

DESCRIPTION

FIG. 1 is a right side perspective view of a toilet brush showing our new design;

FIG. 2 is a right side view thereof;

FIG. 3 is a front view thereof;

FIG. 4 is a left side view thereof;

FIG. 5 is a top plan view thereof;

FIG. 6 is a bottom plan view thereof;

FIG. 7 is a rear view thereof;

FIG. 8 is a right side perspective view of an alternate embodiment wherein the stippling represents a contrasting material;

FIG. 9 is a right side view of FIG. 8;

FIG. 10 is a front view of FIG. 8;

FIG. 11 is a left side view of FIG. 8;

FIG. 12 is a top plan view of FIG. 8;

FIG. 13 is a bottom plan view of FIG. 8; and,

FIG. 14 is a rear view of FIG. 8.
